UNITED STATES PATENT OFFICE.

CLYDE ODEN AND HENRY R. MOORE, OF SYRACUSE, NEW YORK, ASSIGNEES TO NU-WAY MILKER COMPANY, OF SYRACUSE, NEW YORK, A CORPORATION OF NEW YORK.

TEAT CUP.

Application filed February 25, 1920. Serial No. 361,116.

To all whom it may concern:

Be it known that we, CLYDE ODEN and HENRY R. MOORE, of Syracuse, in the county of Onondaga, in the State of New York, have invented new and useful Improvements in Teat Cups, of which the following, taken in connection with the accompanying drawings, is a full, clear, and exact description.

10 This invention relates to certain improvements in teat cups for milking machines.

Broadly, the object of the invention is to produce a teat cup which is simple, strong and durable in construction, efficient in operation, and capable of being readily assembled for use, or taken apart for cleaning or repairing.

Specific objects relate to the details of construction of the teat cup, as will more 20 fully appear from the following description, taken in connection with the accompanying drawings, in which:

Figure 1 is an elevation of the teat cup.

Figure 2 is a vertical section through the 25 same.

Figure 3 is an elevation of the clamping mouth piece.

Figure 4 is a vertical section through the clamping ring.

30 The teat cup as shown, comprises a casing —1— a flexible, collapsible tube or inflation —2—, a nipple —3—, which may be of glass, metal or other suitable material, and a clamping ring —4—, externally threaded for adjustable connection to the threaded lower end of casing —1—, for securing the nipple —3— and lower end of the flexible lining —2— in proper position.

The feature of our present invention resides 40 specifically in the combination with the upper cylindrical portion of the casing, of a peculiarly shaped and formed clamping mouth piece, designed to properly define the opening into the inflation, and at the same time acting to positively secure the upper end of the flexible lining or inflation in position relative to the casing.

For this purpose the clamping mouth piece —5— is of tubular form, substantially 50 circular in cross section, and having upon its exterior surface a plurality, in this instance two substantially parallel circumferential grooves or channels —6— and —7—.

The groove —6— is defined by a pair of 55 outwardly projecting flanges —8— and —9—, of substantially equal radii so as to form a substantially symmetrical groove. The lower wall of flange —9— is inclined downwardly at ten (10) to constitute the 60 upper wall of the groove —7—, and the base —11— of said groove may, if desired, be substantially flat. The lower wall —12— of the groove —7— is formed by a flange —13— projecting outwardly from the body 65 of the clamping ring, a distance somewhat less than the projection of the flanges —8— and —9—. In other words, the radius of the circle defined by flange —13— is somewhat less than the radius of the circle determined by the outer surface of flange —9—. The mouth piece —5— is preferably formed with a downwardly tapered wall —14—, extending some distance from flange —13— to permit the insertion of the said mouth 70 piece within the inflation —2— with little or no difficulty.

The upper end of the casing —1— is not flared outwardly in the usual manner of manufacturing this type of teat cup, 80 but is of substantially uniform diameter throughout.

In operation, the flexible lining —2— when withdrawn, or partially withdrawn from the casing —1—, has its upper end 85 stretched over the mouth piece —5— until the upper edge of the inflation lies adjacent the flange —8—. The mouth piece —5— is then pressed downwardly in the upper end of the casing —1— until the position shown 90 in Figure —2— is reached, or approximately that position.

The lower end of the inflation is then fitted over the nipple —3— and the locking ring —4— screwed into proper position. 95 As clearly shown in the drawing, the flange —13— fits within the upper end of casing —1— in a manner to somewhat compress the interposed inflation so that it expands into the groove —7—. The flange —9— is 100 of such a diameter that when the inflation extends over the same, it will not pass within the casing —1—, and the inflation is confined within the upper edge of the casing and the exterior surface of the flange. The 105 result of this construction is that when the mouth piece is pressed downwardly within casing —1—, the upper edge of the casing

tends to move the exterior portion of the inflation vertically, whereby the upper edge of the inflation is automatically turned inwardly and forced into the groove —6—. 5 This construction is compact, neat and highly efficient in operation.

Although we have shown and described specific details of construction as perhaps embodies in the preferable form of our invention, we do not desire to limit ourselves to the same as various changes and modifications can be made in the details of form and construction without departing from the invention as defined in the appended 10 claims.

What we claim is:—

1. In a teat cup a tubular mouth piece having a pair of circumferential channels in its periphery.
- 20 2. In a teat cup a tubular mouth piece having a pair of circumferential channels in its periphery, and a tapered wall extending downwardly from the lower channel.
3. In a teat cup a tubular mouth piece having a pair of flanges of different radii, the lower flange adapted to compress an inflation against the inner wall of an enclosing casing, and the upper flange adapted to compress the inflation against the upper 25 edge of the casing, and a groove above said flanges for receiving the upper edge of the inflation.
4. In a teat cup the combination with a 30 casing of substantially circular cross section, and an inflation within the same of a mouth piece within the inflation, having a flange upon its periphery, compressing the inflation against the casing, a channel above the flange for receiving the inflation, a second flange compressing the inflation against 35 the upper edge of the casing, and a groove

above the second flange for receiving the edge of the inflation.

5. In a teat cup, a casing of substantially circular cross section, an inflation within 45 the casing, a mouthpiece extending within the inflation and having three substantially parallel outwardly extending circumferential flanges forming a pair of spaced circumferential channels, one of said flanges compressing the inflation against the interior of the casing, another of said flanges compressing the inflation against the upper edge of the casing, and the third flange adapted to confine the upper edge of the inflation in the upper channel. 55

6. In a teat cup, a casing, an inflation within the casing, a tubular mouthpiece extending within the inflation and having a pair of circumferential flanges, one of said flanges compressing the inflation against the interior wall of the casing, and the other flange compressing the inflation against the upper edge of the casing. 60

7. In a teat cup, a casing, an inflation within the casing, a tubular mouthpiece extending within the inflation and having a pair of circumferential flanges, one of said flanges compressing against the interior wall of the casing, the other flange compressing the inflation against the upper edge of the casing, and a circumferential channel above the last named flange adapted to receive and retain the upper edge of the inflation. 65

In witness whereof we have hereunto set our hands this 19th day of February, 1920.

CLYDE ODEN.
HENRY R. MOORE.
